METHOD OF KNITTING

Jack Markowitz, Brooklyn, N. Y., assignor to
Pennant Knitting Mills, Inc., Brooklyn, N. Y.

Application April 6, 1940, Serial No. 328,168

2 Claims. (Cl. 66—12)

This invention relates to a method and machine for knitting a fabric of shirred or gathered construction, substantially of the type shown and described in my patent application for knitted fabric filed March 19, 1940, Serial No. 324,801, now Patent No. 2,201,269.

It is primarily within the contemplation of this invention to produce a fabric of the above general description embodying therein a yarn of elastic properties in such manner that the entire fabric is substantially in one plane when the elastic element is in its fully elongated condition, and in a gathered or puckered condition when the elastic element is permitted to contract.

It is another object of my invention to provide a convenient means of incorporating such elastic element while in its fully elongated condition during the knitting process, and permitting such elastic element to contract to its normal condition after the performance of the knitting steps.

In the process of incorporating such elastic elements into the body of the fabric there is the danger of a slipping of these elements with respect to the body yarn, when ordinary knitting methods are employed—a condition which would produce an uneven bunching together of the fabric at scattered portions thereof. It is hence another object of my invention to provide a method of so tying in the elastic elements as to prevent such a slippage, thereby producing a fabric of uniform and presentable appearance.

Another object of this invention is to provide means for reinforcing the elastic elements in a fabric of the above described character.

And it is within the further contemplation of my invention to accomplish the aforesaid objectives without the necessity of altering the structure of conventional circular open top knitting machines.

Other objects, features and advantages will appear from the drawings and the description hereinafter given.

Referring to the drawings,

Figure 1 is an enlarged diagrammatic representation of one form of fabric made by the method of this invention, the elastic yarn being shown in its fully elongated condition.

Figure 2 is a semi-diagrammatic elevation of a knitting machine containing my invention adapted to knit the fabric of Figure 1.

Figure 3 is a side sectional view of the friction tensioner employed in the practice of my invention for maintaining the elastic yarn in its elongated condition.

Figure 4 is an end view of the device of Figure 55

3, showing the general direction of the elastic yarn engaged thereby.

Figure 5 is a semi-diagrammatic development of a portion of a knitting machine, preferably of the open top circular type, illustrating the arrangement of elements for the practice of my invention.

Figures 6 and 7 represent upper and lower positions, respectively, of a needle at a jersey stitch feed, illustrating the relative positions of the needle, yarn and sinker.

Figures 8 and 9 represent upper and lower positions, respectively, of two adjacent needles at a tuck stitch feed, showing the relative positions of the needles, yarn and sinkers.

Figures 10 and 11 represent upper and lower positions, respectively, of two adjacent needles at the elastic yarn feed, showing the relative positions of needles, yarn and sinkers.

Figures 12 and 13 represent the upper and lower positions, respectively, of needles at the double yarn feed at which jersey stitches are made, showing also the relative positions of needles, yarn and sinkers, and

Figure 14 is a diagrammatic representation showing the position of the elongated elastic yarn with respect to the adjacent needles drawn down by the stitch cam.

In Figure 1 will be seen the various courses

30 constituting the fabric, including jersey stitch course 15a containing yarn 15, jersey stitch course 16a containing yarn 16, tuck stitch course 17a containing yarn 17, jersey stitch course 18a containing yarn 18, elastic course 19a containing

25 the elastic yarn element 19, reinforcing jersey knit course 20a containing double yarn 20, tuck stitch course 21a containing yarn 21, jersey stitch course 22a containing yarn 22 and jersey stitch course 23a containing yarn 23. It will thus be

seen, that the fabric illustrated contains an elastic element embodied within a basic knit portion formed of body yarn which may be of jersey stitch formation. It is, however, understood that other forms and designs of stitches may be employed in the basic knit portion of the fabric within the scope and intent of this invention.

The fabric illustrated in Figure 1 merely shows a single elastic element 19 although any number of such elements may be incorporated in parallel spaced courses. It is believed unnecessary to illustrate more than one such elastic course for the purpose of describing my invention.

It will be observed that the elastic element 19 has on each side thereof a course of tuck stitches 17a and 21a, respectively.

It is also preferred that a reinforcing yarn 20 be employed, this being formed with undulating stitches alternately disposed in front of and behind said elastic yarn 19. Although a double yarn 20 is here illustrated, it is also within the contemplation of my invention to employ any other type of reinforcing yarn means of increased proportions or strength. It will also be observed that inasmuch as the free portions 24 and 25 of the tuck stitches in courses 17a and 21a, respectively, are not knitted into the fabric, short floats are formed, enabling the formation of the relatively long loops 26 and 27, respectively, the excess yarn in such loops being taken from the tuck stitches.

In producing a fabric in accordance with that illustrated in Figure 1, a conventional circular open top knitting machine 28 may be employed containing a plurality of sinkers 29 one of which is diagrammatically shown in Figure 5—these sinkers being operated by a conventional sinker actuating cam not herein described inasmuch as its operation is well known in the art. The machine contains a cylinder with a plurality of vertically movable needles thereabout, each being adapted to be raised or lowered by suitable elevating and depressing mechanisms. In the particular form of my invention illustrated, the needle cylinder is stationary—the yarn stand and cam ring being rotatable, although it is understood that this invention is equally adaptable for use with a rotating cylinder. The yarn stand 30 is adapted to operatively support yarn cones 31 thereon, as well as the cone 32 containing the elastic yarn 19.

It is within the contemplation of this invention to feed the elastic yarn 19 to the needles in its elongated condition, and with this end in view I provide tensioning means intermediate the yarn cone 32 and the cylinder of the machine. The tensioning means illustrated include the sinuous wire element 33 and the friction tensioner 34 through which the elastic yarn passes on its way to the needles. As the yarn 19 is drawn through the convolutions of element 33, it encounters a certain amount of frictional resistance, thereby causing the portion 35 of the yarn to be slightly elongated. The yarn 19 is thereafter engaged between the two friction plates 36 of the tensioner 34, these plates being urged towards each other by the helical spring 37 mounted over the bolt 38. The said bolt extends through central apertures in plates 36 and is attached to portion 39 associated with the framework of the machine. The nut 40 maintains the inner of the friction plates 36 in spaced relation to portion 39; and the nut 41 is adapted to adjust the tension in spring 37 so as to control the amount of frictional resistance to which the yarn 19 is subjected during its passage therewith. The nut 41, in the practice of my invention, is so adjusted as to cause portion 42 of yarn 19 to be elongated substantially to its fullest length, so that it may be operatively incorporated into the fabric while in its stretched condition, in the manner to be more fully hereinafter set forth.

Figure 5 illustrates seven feeds of the machine including one feed for laying in the elastic yarn 19. This cycle of feeds can of course be repeated throughout the circumference of the cylinder. The needles are adapted to be operatively moved to three positions, the lowest or welt position being substantially at sinker or cast-off level 43, the tuck position substantially at level 44 and the latch-clearing position substantially at level 45.

In producing course 16a, the needles 46 are gradually elevated by surface 47 of cam 48 from the welt position 43 to the latch-clearing position 45, taking the yarn 18 below the hooks of the needles, substantially as indicated in Figure 6. Thereafter the needles are drawn down by the stitch cam 49 to the welt or casting-off level, to produce a loop, as indicated in Figure 7. The approach cam 50 thereafter elevates the needles to the position where they will be operatively received by the pattern wheel 51 which is arranged to elevate the needles alternately to latch-clearing and tuck positions. The needle 52, elevated to latch-clearing position, will take the tuck yarn 17, as illustrated in Figure 8, the latch being free of the previously formed loop; but the needle 53, elevated only to tuck position, will take tuck yarn 17 while its latch is engaged by the previously formed loop, as shown in Figure 8. In this manner alternate tuck and jersey stitches will be formed in this course when the needles are drawn down by stitch cam 54 to the positions illustrated in Figure 9. Thereafter the needles are again elevated by cam 55 to the latch-clearing level 45, at which point they will take yarn 18 to form a jersey stitch when drawn down by stitch cam 56.

The needles thereafter are again elevated by cam 57 until they are in a position to be operatively received by the pattern wheel 58 which is so arranged as to operatively elevate alternate needles to tuck positions, the unelevated needles remaining at welt level. The upper needles 59 will engage the elongated elastic yarn 19 at tuck level, as shown in Figures 5 and 10; but the yarn so engaged by alternate needles 59 will be above the adjacent needles 60 at welt level. Thereafter, when the needles are drawn down by stitch cam 61, the elongated yarn 19 will be disposed underneath hooks of alternate needles 59 and behind needles 60, as indicated in Figures 11 and 14. It is apparent that after yarn 19 is operatively released from engagement with the needles, it will gradually contract as the tube of knitted fabric is drawn down. In contracting, yarn 19 will carry with it the loops of interlocking stitches, producing a gathering or puckering effect. However, if the yarn 19 is not securely tied in, there may be a slipping between the interlocking loops and elastic yarn 19, thereby preventing a uniform gathering effect. To reduce the possibility of such an occurrence, I have introduced a further step of tying in the elastic yarn by a reinforcing yarn 20 which, in the preferred form of my invention, consists of a double strand of yarn as shown.

After the needles are disengaged from stitch cam 61, they are again elevated by cam 62 to a latch-clearing position, at which level they will take said reinforcing yarn 20, as indicated in Figures 5 and 12. Then the stitch cam 63 draws the needles down to produce jersey loops as indicated in Figure 13, thereby forming reinforcing course 20a.

Tuck stitch course 21a is thereafter formed by having cam 64 elevate the needles to a position where they will be operatively received by the pattern wheel 65 which is arranged to elevate the needles alternately to latch-clearing and tuck positions, whereafter they are drawn down by stitch cam 66 to begin a new cycle.

It will be observed (see Figure 1) that the elastic yarn 19 extends in a straight line alternately behind loops 20b of the double yarn 20 in one wale, and between the single and double yarn loops 26 and 27 in the next wale. And it will

be further observed that the regions 19b of the elastic yarn 19 are firmly tied in between the long loops 26 and 27, thereby preventing slippage between the elastic and the interlocking yarns. The use of the relatively heavy double yarn 20 enhances this tying-in effect, inasmuch as that portion of loop 27 behind region 19b is sufficiently bulky to force elastic yarn 19 against loop 26; and in this manner said loops 26 and 27 cooperate to frictionally hold the elastic yarn against slippage. Furthermore, the double yarn 20 or the equivalent thereof serves the additional purpose of reinforcing the fabric at the region of the elastic strands 19.

It is thus apparent that by the method of this invention, shirred fabrics can be readily produced on a conventional circular open top knitting machine, the puckers being uniformly distributed due to the special method of tying in the elastic yarn.

It is of course understood that other additional forms and modifications of the apparatus and adaptations of the method constituting this invention can be employed beyond and in addition to those hereinabove described, all within the scope of the appended claims.

What I claim is:

1. In a method of knitting on a circular open-top latch needle machine, the steps of elevating successive needles to yarn taking positions, operatively supplying yarn to said needles, drawing down said needles to a casting-off level for operatively knitting previously formed stitches, elevating certain of said needles substantially to tuck level, operatively supplying to said elevated needles stretched elastic yarn, depressing the needles to a casting-off level thereby forming floats of the stretched elastic yarn across the

needles that were not elevated at the tuck feed, elevating the needles to a latch-clearing position, operatively supplying a double strand of reinforcing yarn to the needles at said latter position, and drawing down the needles to a casting-off position for tying in with said reinforcing yarn the stretched elastic yarn.

2. In a method of knitting on a circular open-top latch needle machine, the steps of elevating successive needles alternately to latch-clearing and tuck levels, operatively supplying yarn to said needles, drawing down said needles to a casting-off level for operatively knitting alternate loops of previously formed stitches, elevating the needles to yarn taking positions, operatively supplying yarn to said needles, drawing down said needles to a casting-off level for operatively knitting previously formed stitches, elevating certain of said needles to tuck level, operatively supplying to said elevated needles stretched elastic yarn, depressing the needles to a casting-off level thereby forming floats of the stretched elastic yarn across the needles that were not elevated at the last-mentioned tuck feed, elevating the needles to a latch-clearing position, operatively supplying reinforcing yarn to the needles at said latter position, drawing down the needles to a casting-off position for tying in with said reinforcing yarn the stretched elastic yarn, thereafter elevating successive needles alternately to latch-clearing and tuck levels, operatively supplying yarn to the needles, and drawing down said needles to a casting-off level for operatively knitting alternate loops of the said reinforcing yarn, whereby there will be a course of tuck stitches on either side of and in adjacent relation to the elastic yarn course.

JACK MARKOWITZ.
